HYDROCARBON CONVERSION

August H. Schutte, Hastings on Hudson, N. Y.,
assignor to The Lummus Company, New York,
N. Y., a corporation of Delaware

Application May 28, 1948, Serial No. 29,751

2 Claims. (Cl. 196—52)

1

This invention relates to hydrocarbon conversion and, in particular, to the formation of coke concurrently with the vaporization and cracking of heavy hydrocarbons such as "bottoms" and hydrocarbon residuals wherein the coke formed in the aforesaid reaction is deposited on discrete particles of a free-flowing non-agglomerating bed moving continuously by gravity alone. It is a continuation-in-part of my copending application Serial No. 577,707, filed February 13, 1945, and entitled Improvements in converting hydrocarbons.

It is an object of this invention to make novel provision for the uniform distribution of liquids on the particles of the continuously moving gravity packed bed of contact material which moves downward through a sealed reaction chamber solely by gravity.

It is a further object of this invention to provide a new and improved method for securing the conversion of a hydrocarbon liquid in the presence of a continuously moving bed of contact material wherein the particles are uniformly coated with the non-vaporizable portion of the hydrocarbon.

Further objects and advantages of my invention will appear from the following description of preferred forms of embodiment thereof taken in connection with the attached drawing in which:

Figure 1 is a view partly in elevation and partly in vertical section of a reaction unit showing one form of liquid distributing means.

Figure 2 is a vertical section on the line 2—2 of Figure 1 on an enlarged scale.

Figure 3 is an elevation, with parts in section and parts broken away, of a modified form of reaction chamber.

Figure 4 is a horizontal cross section, substantially on the line 4—4 of Figure 3.

Figure 5 is a vertical section on the line 5—5 of Figure 4.

In accordance with my above mentioned application and as pointed out in a copending application Serial No. 3,747, filed January 22, 1948, such application being a continuation-in-part of an earlier, and now abandoned, application Serial No. 510,119, filed November 13, 1943, of which I am a coinventor, the disposition of heavy hydrocarbon by-products of cracking, distillation and like operations, comprising bottoms, tars and the like has represented a major operating problem in the petroleum industry. While it has been recognized that the conversion of a part of these by-products to coke along with the formation of

useful and valuable conversion products would solve this problem, at least to a large degree, all former attempts have resulted in the use of expensive, complicated and cumbersome mechanisms difficult to service and of relatively low efficiency.

The present invention is particularly adapted to the uniform distribution of these heavy hydrocarbon feeds in liquid or substantially liquid form onto a compact, free-flowing gravity packed bed made up of discrete porous solid particles which move downward solely by gravity and in which the control of temperature and rate of feed of the charge and temperature and rate of feed of the bed, as well as the provision of a predetermined length of travel for bed particles, is so arranged as to avoid agglomeration. It has thus been found possible to obtain the continuous desired vaporization of the lighter portions of the charge and to form a dry coke coating on the discrete particles.

It is to be noted, however, that the uniform distribution of the charge is of substantial importance for if agglomeration occurs the bed stops moving and local low temperatures develop and the entire mass may tend to stop flowing.

I have found that it is desirable to avoid the introduction of any air or oxygen containing gas into the reaction chamber to prevent the formation of combustion products which would tend to dilute the vapors resulting from the hydrocarbon conversion. It is also not only unnecessary but undesirable to increase the temperature of the bed as it flows downward by gravity and preferably the hotter portion should be established at the top so that there is no tendency of the rising vapors to condense and coke on the surface of the reactor.

More particularly referring to the drawings, Figure 1 represents a pilot plant size unit the main body 10 of which consists of a tube of nominal diameter surmounted by a hopper top generally indicated at 12 through which projects the contact material inlet pipe 14. The contact material in turn is contained in a hopper 16 and the contact material in passing through the inlet pipe 14 into the larger chamber 10 will form a flowing pile of material the outline of which is shown at 18. The angle of this pile or mass is a function of the angle of repose of the material.

Between the top of the pile 18 and the dome of the hopper 12 is a vapor releasing space generally indicated at 20 from which the vapors may be removed through the line 22. It will, of course, be understood that the contact material moves

downward by gravity out the bottom of the tube 10. Usually a control valve 23 is provided in the outlet pipe.

The feed spreader or distributors in the present apparatus are generally indicated at 24 and as more particularly shown in Figure 2, it consists of a circular or annular ring which is mounted adjacent the end of the granular particle inlet 14. Conveniently this may be mounted directly on the end of the tube 14 and is preferably provided with a series of apertures 26. In the particular case there are four which are spaced substantially uniformly around the periphery of the tube 14. As shown in large cross section in Figure 2, the openings are on a downwardly inclined angle so that the contact material which passes down through the conduit 14 and as it flows into the piles 18, will be completely coated with the charge. The hydrocarbon inlet is indicated at 28.

It will thus appear that the feed is applied to the discrete bed particles when they are undergoing movement in the flowing piles from the material inlet to the reactor chamber 10. Uniformity of feed is assured; no liquid will be thrown against the wall and premature coking will be avoided. The construction is simple and effective and the feed openings are continuously kept clean by the movement of the particles across their surface.

The discrete particles of contact material may be either inert porous contact material such as "Kopper's" coke, petroleum coke, alundum, carbondum, or other materials or, alternatively, it may be of a catalytic type such as silica gel or other known catalyst depending upon the reaction desired. Preferably the bed particles are maintained in a range of from $\frac{1}{8}$ in. to $\frac{3}{4}$ in. major dimension and they may be in lump, pellet or extruded form. For the conversion of heavy hydrocarbons, it is sufficient if they are introduced in the inlet 14 at a temperature at from 800 to 1300° F. The hydrocarbons will, of course, be introduced at a suitable temperature in the usual range of 700° F. to 900° F. The vapors under such conditions will be of prime value for further cracking, usually having a gas oil composition with low carbon content so that they may be directly introduced into a conventional catalytic cracking unit for the production of high grade gasoline. If a cracking reaction is desired, the contact material being catalytic, and the temperatures and charge being adjusted accordingly, the vapors will of course be of high quality gasoline type.

Ordinarily the reaction is carried out at relatively low pressures which may range between 2 pounds p. s. i. g. and 60 pounds p. s. i. g., largely depending upon the pressure required to convey the product vapors to subsequent process equipment.

Reference is made to Figures 3 to 5 of the drawing which illustrate an adaptation of the construction shown in Figures 1 and 2 where the reactor generally indicated at 30 is adapted for full size commercial operations and in which from 50 to 300 tons of the contact material will pass through per hour. In such case, the reactor is a tank like elongated enclosure having a cylindrical wall 31 and frusto-conical end portions continuing therefrom and designated 32 and 34, respectively. Leading into the top frusto-conical end portion 32 is the inlet 35 through which the heated porous bed particles are sent to form the free flowing gravity bed. A suitable outlet 36 extends from the lower frusto-conical end por-

tion 34 and will be connected to a suitable delivery duct for transferring the bed particles with coke deposits to any suitable collection station. The lower end of the reactor 30 is provided with suitable known means not shown for controlling the uniformity of passage of bed particles through the reactor 30 and a valve 37 will be used to vary the rate as desired.

Leading into the frusto-conical end portion 32 adjacent its junction with the inlet 35 is a sealing steam inlet 38 through which sealing steam is applied to the interior of the reactor 30 and feed leg to prevent the passage of cracked vapors and the like upwardly through the bed material and out the inlet 35. A similar sealing steam inlet 39 is provided at the junction of the frusto-conical end portion 34 and the outlet 36 to prevent the passage of vaporous products downwardly out of the reactor 30 with the bed particles and coke deposits issuing from the outlet.

As shown, the interiors of the frusto-conical end portions 32 and 34 may be lined with insulation 40 and similar insulation 41 may be provided in the interior of the outer shell of the cylindrical portion of the reactor 30, all of said insulation being arranged between the metallic outer shell of that portion and a generally cylindrical interior metallic lining 42 which prevents abrasion of the insulation by the downwardly passing bed material.

Within the upper part of the cylindrical body of the reactor there is a wall or baffle 44 which is provided with a plurality of apertures 45 opening into down pipes or conduits 46 which extend into the hydrocarbon feed and vapor release space or conversion zone below the wall or baffle 44 and provide substantially uniform distribution of the bed material fed through the baffle. The vapor outlet 47 extends from the feed and vapor release space on the interior of the reactor 30 immediately below the wall or baffle 44 to any suitable collecting station to which it is desired to convey the vaporous products of the reaction occurring within the reactor 30.

In the bed feed zone above the baffle or wall 44, the particles are dry, with their pores substantially empty and free of foreign matter, coatings or deposits. These particles are within the temperature range described above. Upon passing downwardly through the downpipes 46 and past the spreaders 48 they enter frusto-conical masses or flowing piles or "cones of repose" depending upon the shape of the downpipes 46 wherein the particles are in substantial movement. Hydrocarbon liquid supplied by the spreaders 48 in fine streams is spread upon the moving discrete particles. In the particular case illustrated, the openings 46 are shown as rectangular but they may be of other shapes, including circular in cross section as shown in Figure 2, if desired.

The feed spreading mechanism comprises a plurality of perforate pipe-like conduits 48 all connected with a common header 49. As shown in Figures 4 and 5, the spreaders or distributors 48 are preferably located adjacent the edges of the depending downpipes 46 so that the hydrocarbon feed material is contacted with the hot porous moving bed particles issuing from the downpipes 46 as shown in Figure 3.

The feed spreaders or distributors are so located at the edge of the downpipes that the heavy hydrocarbon material comprising the feed is allowed to pass from the apertures 50 in the spreaders or distributors 48 in relatively fine

streams (as distinguished from atomizing sprays) to the particles which are moving down as flowing piles over and within the frusto-conical portions of the bed, i. e., the cones of repose immediately adjoining the bed material in the interior of the downpipes 46, whereby the feed is applied uniformly to the discrete bed particles when they are undergoing movement in the aforesaid cones of repose or flowing piles. The thus injected feed streams applied at opposite sides of the top portion of each flowing pile are completely confined by the contact material, as shown in Fig. 3, so that the charge liquid will be prevented from carrying out of the path of the material.

Upon spreading the feed upon the bed particles a part thereof is "flashed off" or evaporated upon contact with the hot bed particles and withdrawn as useful vapors which may be taken off, for further processing, to any suitable station. The remainder of the feed which does not "flash off" or evaporate is taken up or received by particles substantially entirely whereby formation of sticky films between the discrete bed particles sufficient in depth or thickness to destroy the free flowing properties of the bed is totally obviated. As much as 50% of oil by weight to contact material may be applied without causing agglomeration depending upon the nature of the contact material. An entirely impervious material such as beach gravel will ordinarily receive about 10% by weight of hydrocarbon under my operating conditions.

As these loaded bed particles pass downwardly by gravity as a column of greater horizontal cross sectional area than the streams through the body of the reactor 30, sufficient residence time is provided for the coking reaction to proceed to completion or, in other words, for the liquid hydrocarbon load on the particles to be thermally converted or cracked into lighter hydrocarbon vapors which pass up through the bed to the vapor outlet 47 leaving a residue of dry coke deposit. The particles in this condition pass out of the reactor through the outlet 36. This residence time at the normal operating temperatures may range from 10 to 30 minutes. In such case a depth of bed below the feed point must be provided which is greater than the free flowing depth of the charge which at the temperatures under consideration has a viscosity of about one-tenth that of water. A minimum depth of five feet and a preferred depth of thirty to fifty feet is the range for most effective dry coke formation.

The process illustrated by the embodiment of Figures 1 and 2 forms the subject matter of my copending divisional application Serial No. 100,417, filed June 21, 1949, and entitled Method for hydrocarbon conversion.

While I have shown and described a preferred form of embodiment of my invention, I am aware that modifications may be made thereto and I therefore desire a broad interpretation of my in-

vention within the scope and spirit of the description herein and of the claims appended hereinafter.

I claim:

1. A process for conversion of a charge of high boiling liquid hydrocarbons which comprises passing a compact column of particle form contact material vertically downward through an elongated conversion zone, introducing said contact material at a suitable conversion supporting temperature into the upper end of said conversion zone as a plurality of confined streams of appreciably less cross-sectional area than said compact column to form upon release a series of flowing piles of contact material extending to the upper end of said column and defining a vapor collection space, withdrawing contact material from the lower section of said zone at a controlled rate to maintain the compact column of contact material within said conversion zone, injecting streams of heavy liquid hydrocarbon charge into opposite sides of each flowing pile of contact material in the upper portion thereof, said injected streams being completely confined by said contact material, and withdrawing vaporous hydrocarbon products through the flowing piles and out of the vapor collecting space.
2. The method of converting a charge of heavy liquid hydrocarbons which comprises passing by gravity alone, a compact column of particle form contact material vertically downward through an elongated conversion zone; introducing said contact material into the upper end of said conversion zone in a plurality of confined streams of appreciably less cross-sectional area than said compact column to form upon release a series of flowing piles of contact material extending to the upper end of said column and defining a vapor collection space at the top of said conversion zone; injecting a plurality of streams of heavy liquid hydrocarbon charge into the top portion of each of said flowing piles of contact material, said injected streams being completely confined by said contact material whereby the charge liquid will be prevented from carrying out of the path of the material, and removing the vaporous products of the reaction from the vapor collection space.
